ATTORNEY.

UNITED STATES PATENT OFFICE.

CHARLES LEIB, OF PHILADELPHIA, PENNSYLVANIA.

DESIGN FOR A HOOK FOR GARMENTS.

SPECIFICATION forming part of Design No. 35,611, dated January 28, 1902.

Application filed December 21, 1900. Serial No. 40,695. Term of patent 14 years.

To all whom it may concern:

Be it known that I, CHARLES LEIB, a citizen of the United States, residing at Philadelphia, in the county of Philadelphia and State of Pennsylvania, have invented and produced a new and original Design for a Hook for Garments, of which the following is a specification, reference being had to the drawings forming part thereof.

10 In the drawings, Figure 1 is a plan view. Fig. 2 is a side view.

The leading or material feature of my design consists of the rear looped ends of the hook, which from a point back of the bill diverge from each other rearwardly and outwardly, each of the diverging ends being in the shape approximately of an arc of a circle.

15 The drawings show the hook as consisting of the shank 4, merging into the diverging 20 curved looped ends 2 at 3, the shank being at

the front of the hook bent upwardly and backwardly to form the bill 6 and outwardly near the front of the hook to form the enlargements 5. 1 represents the loops at the ends of the portions 2. The pronounced diverging 25 curved form given to the looped ends 2 impart a distinctive as well as an ornamental appearance to the hook.

Having described my invention, what I claim as new, and desire to secure by Letters 30 Patent, is—

The design for a hook for garments as herein shown and described.

In testimony whereof I affix my signature in presence of two witnesses.

CHARLES LEIB.

Witnesses:

WILLIAM WEBSTER,
ALBERT L. TAYLOR.
